(57) **CLAIM**

The ornamental design for a tape dispenser, as shown and described.

DESCRIPTION

FIG. 1 is a perspective view of a tape dispenser; FIG. 2 is a left side view thereof, the right side view being a mirror image of the left side view;

FIG. 3 is a top view thereof;

FIG. 4 is a bottom view thereof;

FIG. 5 is a front view thereof; and,

FIG. 6 is a rear view thereof.

The broken lines shown on the serrated cutting element indicate unclaimed subject matter. All other broken lines indicate soft contours of the dispenser.

1 Claim, 2 Drawing Sheets
